UNITED STATES PATENT OFFICE.

JOHN W. BARTON, OF NEW YORK, N. Y.

PRESSURE-FLUID REGULATOR.

1,316,134.

Specification of Letters Patent. Patented Sept. 16, 1919.

Application filed July 13, 1916. Serial No. 108,993.

To all whom it may concern:

Be it known that I, JOHN W. BARTON, of the city of New York, county of Kings, and State of New York, have invented certain new and useful Improvements in Pressure-Fluid Regulators, of which the following is a specification.

My invention relates in general to a pressure controlled fluid regulator and particularly relates to a fuel gas flow regulator controlled automatically by the pressure created in a steam system heated by the regulated gas. One embodiment of the invention has been used successfully to control the gas flow to a dental vulcanizer where the maintenance of a uniform temperature is highly desirable.

The invention contemplates a regulator in the form of a valvular organization disposed within the gas pipe line and controlled by the pressure in a curved tube attached to the valve.

One of the objects of my invention is to provide a compact form of device, of the character indicated, which shall be simple in construction and positive in its action and which at the same time will have a capacity for controlling relatively large volumes of gases within a small volume of space.

Another object of the invention is to provide in the compact device, instrumentalities for delicately adjusting and otherwise affecting one or more valve openings by externally manipulated control mechanism and which will positively insure a closing of the valve or valves on their seats at the preset actuating pressure without the necessity of adjusting any of the valvular parts internally.

Another object of the invention is to provide a construction arranged so that the valvular parts may be easily moved into an inoperative position even under those conditions where unbalanced pressures on opposite sides of the valve tend to resist such movements.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is a view in front elevation of a preferred embodiment of my invention with the front closing cover removed; 60

Fig. 2 is a transverse sectional view taken on the line 2—2 of Fig. 1, looking in the direction indicated by the arrow; and

Fig. 3 is a fragmentary view showing a portion of a plan view at the top of the instrument shown in Fig. 1. 65

In the embodiment of the invention illustrated there is shown a fitting designed to be installed in the gas pipe line leading to the device supplied by the gas. The fitting is in the form of a casting including a pipe member 4 divided by a transverse portion 5 to form an inlet chamber 6 and outlet chamber 7 at opposite ends. The opposite ends of the fitting are threaded as shown at 8 to engage with the threaded end of the interrupted gas line. A valvular mechanism-containing-casing 9 is supported at one side of the pipe member and forms an intermediate chamber 10 open to the inlet chamber 6 through the inlet port 11 in the wall 12 between the pipe member chambers and the intermediate chamber. The casing 9 is shown to be of a general flat cylindrical form the outer end of which is closed by a cover 13 designed to provide ready access to the valvular mechanism hereinafter described. The gas passageway from the intermediate chamber to the outlet chamber 7 includes an open ended centrally disposed tubular member 14 mounted in a suitable bearing 15 supported from the wall 12. A hollow cylindrical hub-member 16 is rotatably mounted upon the tubular member 14 for rotary movement about the axis thereof. 90

The tubular member is provided with several ports 17 placing the interior of the hub-member in communication with the bore of the tubular member. The hub-member has a plurality of curved tubular arms 18 mounted to be revolved therewith. The arms are disposed in a plane at right angles to their axis of rotation and are in the form of small arcs of circles curved in the same direction. The free ends of the arms are open to the chamber 10 and constitute valve seats 19. The arms are cut so that the seats will always be disposed in a plane containing the axis of rotation thereof irrespective of the position of the valve seats on the casing. 105 The valve seats are adjusted in their different positions about the axis of the tubular

member 14 and for this purpose the hub-member is provided with a radially extending arm 20 the outer end of which is provided with a slot 21. A shaft 22 for swinging the arm 20 is rotatably mounted in a stuffing box 23 extending through the back wall 24 of the casing 9. A disk 25 is fixed to the inner end of the shaft which disk is provided with a pin 26 projecting therefrom eccentric from the axis of rotation of the shaft. The pin engages in the slot 21 so as to form a pin and slot connection between the control shaft and the swinging arm 20. The outer end of the shaft is provided with a milled head 27 for actuating the shaft. For the purpose of accurately ascertaining the position of the valve seat the milled head may be provided with graduations 28 movable with the head relative to an indicator 29 carried on top of the casing. The milled head also may be provided with a stop pin or pins 30 designed to engage the indicator to limit the movement of the valve seat in either of its said directions of movement. Obviously the positions of the stop pins 30 may be carried so as to indicate any desired or present maximum or minimum flow through the device.

A plurality of valves 31, one for each valve seat, is mounted within the casing 9 in position closed on its correlated valve seat and thus act singularly or collectively to intercept the passage of gas from the chamber 10 through the tubular member 14. These valves are mounted for rotary movement about the axis of rotation of the valve seats so as to insure the square seating of the valve on its valve seat irrespective of the position of the seat.

In the embodiment of the invention illustrated the valves constitute the free flat ends of a diametrically extending arm 32 rotatably mounted intermediate its length upon a stud-bolt 32¹ also utilized to close the outer end of the tubular member 14. The valve arm is connected to the free end of a curved Bourdon spring tube 34 by means of a link and slot connection 35. The free end of this tube is closed as is usual with devices of this character and the open end is rigidly attached to a nipple 36 the inlet 37 of which extends through the lower side of the casing and is provided with external threads 38 designed to connect with the steam generator or other pressure source for regulating the actuation of the device.

In order to maintain a sufficient supply of gas through the device so as to maintain a pilot light in continuous operation a small perforation 39 is placed in one or more of the valves so as to incompletely shut off the supply of gas to the tubular member when the valves are seated. This perforation also performs the function of a release valve and thus insures an easy movement of the valve

off its seat where unequal pressures are on opposite sides of the seated valves.

If desired, the device may be provided with a by-pass for admitting the gas from the intermediate chamber through the outlet without passing through the pressure control valvular device hereinbefore described. For this purpose the wall 12 is provided with a port 40 frusto-conical in outline and designed to be closed by means of a valve 41 the stem 42 of which is threaded and passed through a stuffing box 43 in the side of the pipe member. The exterior end of the stem is provided with a milled head 44 for moving the valve manually to and from its closing position engaging the seat.

In operation, the milled head for swinging the valve seats is rotated until the desired position of the valve seats with reference to the normal inactive position of their correlated valve is attained. As the temperature of the steam or other pressure medium in the curved arm rises the effect of such increase pressure on the tube is to cause the same to straighten out and thereby act through the link connection to draw the valve or valves toward and into engagement with their correlated valve seats. It is obvious that the closer the valve seat is to the valve the less pressure will be required to move the valve into its closing position on the seat and, contrarily, the farther the valve seat is away from its valve the greater is the pressure required to close the valve onto its seat.

By means of this device a nicety of adjustment is provided, which will insure the accurate closing of the valve at the preset pressure at which it is desired to actuate the device. Should it be desired to admit a flow, either constantly or at will, through the device the by-pass valve may be regulated off its seat to effect the desired flow.

By means of a device of this character, it is obvious that the valve will close squarely on its seat irrespective of the initial position of the seat with reference to the valve and this square closing and adjustment is effected without the necessity of opening the casing to adjust any part of the valvular mechanism, the entire adjustment being provided by the one screw exteriorly of the casing. A valvular mechanism of the class disclosed is particularly susceptible for installation within a small volume casing and provides a means for installing a plurality of openings all within a limited space. Ready access is provided to all of the parts, simply by removing the outer cover and all of the parts are peculiarly susceptible for ready demounting, repairing or substitution.

By shifting the position of the stop pin or pins it is possible for the operator to leave

the instrument quickly, setting the valve seat so as to permit a small flow through the device without stopping to read the scale. Simply rotating the milled head 28 as far as 5 permitted by the set pin will insure the proper predetermined flow.

While I have shown and described, and have pointed out in the annexed claims, certain novel features of my invention, it will 10 be understood that various omissions, substitutions and changes in the form and details of the device illustrated and in its operation may be made by those skilled in the art without departing from the spirit of the 15 invention.

Having thus described my invention, I claim:

1. In a device of the class described, the combination of a conduit in the form of a 20 curved pipe having an open end providing a valve seat, said conduit mounted for rotary movement about a fixed axis of rotation and said seat disposed in a plane passing through said axis of rotation, a pipe fixedly mounted 25 in position concentric with said axis of rotation for receiving fluid from said conduit, a valve mounted for rotary movement about said axis of rotation and designed to engage said seat squarely in its different adjusted 30 positions, means for swinging the curved pipe independently of the supply pipe so as to adjust the position of said seat toward and from the normal position of the valve and means operatively connected to said 35 valve to move the same relative to its seat.

2. In a device of the class described, the combination of a conduit having a plurality of open ends providing valve seats, said 40 seats mounted for rotary movement about a fixed axis of rotation and disposed in a plane passing through said axis of rotation, valves mounted for rotary movement about said axis of rotation and designed to engage said seats squarely in their different adjusted 45 positions, means for adjusting the position of said seats toward and from the normal position of the valves and pressure controlled means operatively connected to the valves to move the same toward their seats 50 with increase in pressure.

3. In a device of the class described, a conduit, a hollow hub member rotatably mounted on said conduit and opened thereto, a tubular inlet arm having one end open to 55 said hub members and having its opposite end revolvably mounted for movement about the axis of said conduit into any desired angular position, said opposite end provided

with a valve seat adjustable with the movement of the tubular arm, a spring having 60 one end fixed in place, a valve linked to a movable part of the spring and adapted to be moved thereby into engagement with said valve seat in its several positions to close communication through said conduit, 65 said spring designed to be effected by pressure applied thereto to close the valve on to its adjustable seat and thus intercept the flow through said conduit, hub member and tubular member. 70

4. In a device of the class described, a containing casing, a plurality of inlet ports movably mounted in said casing for adjustment about a fixed axis of rotation, and in the aggregate providing a relatively large 75 area inlet, means for simultaneously adjusting the position of said ports, a plurality of valves one for each port, operatively mounted to close the same, and a curved hollow tube operatively connected to said valves to 80 close the same by a pressure condition in said tube.

5. In a device of the class described, a pipe provided with an inlet at one end, an outlet at the other end and a separating partition 85 therebetween, a casing having an opening thereto from the inlet end of the pipe, a conduit leading from the casing to the outlet end of the pipe, a pressure controlled valvular mechanism demountedly positioned on 90 the part of the conduit in said casing for controlling the flow through said conduit, said casing provided with an opening affording direct access to said valvular mechanism and a cover for closing said opening. 95

6. In a device of the class described, a pipe provided with an inlet at one end, an outlet at the other end, and a separating partition therebetween, a casing having an opening thereto from the inlet end of the pipe, a tubular member for placing said conduit in fluid communication with the outlet end of the pipe, a hub member rotatably mounted on said tubular member, a curved tubular arm opening into said hub member and provided with a valve controlled opening thereto from the casing, a valve rotatably mounted on said hub member and pressure actuated means connected to said valve to close the opening and means for supplying a fluid 105 under pressure to said pressure actuated means. 110

Signed at New York city, in the county of New York and State of New York, this 12th day of July, A. D. 1916.

JOHN W. BARTON.
